UNITED STATES PATENT OFFICE.

THOMAS LYCETT AND CHARLES DICKSON HOUSEMAN, OF GASTONVILLE, PENNSYLVANIA.

SWITCH-LOCK.

No. 914,294.

Specification of Letters Patent. Patented March 2, 1903.

Application filed March 6, 1903. Serial No. 419,595.

To all whom it may concern:

Be it known that we, THOMAS LYCETT and CHARLES DICKSON HOUSEMAN, citizens of the United States of America, residing at 5 Gastonville, in the county of Washington and State of Pennsylvania, have invented certain new and useful Improvements in Switch-Locks, of which the following is a specification, reference being had therein to 10 the accompanying drawing.

This invention relates to switch locks, and the primary object of our invention is to provide simple and effective means for holding a switch arm in a fixed position, whereby 15 a railway switch cannot be misplaced or tampered with.

A still further object of our invention is to provide a simple and inexpensive switch lock that can be easily and quickly manipulated to release a switch arm or hold the same in a fixed position.

With the above and other objects in view which will more readily appear as the invention is better understood, the same consists in the novel construction, combination and arrangement of parts to be presently described and then specifically pointed out in the appended claims.

In the drawings:—Figure 1 is a plan of a 30 switch equipped with our improved lock, Fig. 2 is a front elevation of our switch lock, partly broken away, and partly in section, Fig. 3 is a side elevation of the same, partly broken away and partly in section, Fig. 4 is 35 an elevation of a semaphore switch equipped with our lock, and Fig. 5 is a perspective view of one of the pins used in connection with the lock.

In the accompanying drawings, 1 designates a track supported upon ties 2, some of 40 which extend to one side of the track to provide bearings 3 for a crank shaft 4 having a switch arm 5, this switch arm being employed to move the switch tongues 6 by 45 virtue of a rod 7 connecting with the crank shaft 4.

Adjacent to the shaft 4 we locate our switch lock for holding the arm 5 in a fixed position. The switch lock comprises a 50 standard 8 slotted, as at 9, to receive the switch arm 5. The standard is recessed as at 10, and bifurcated as at 11, for a pivoted latch 12, said latch having a suitable latch 13. The latch 12 is provided in its outer 55 face with a concavity 14 for an arm 15, said arm being pivoted within the concavity by

a pin 16. Pivots connected to the ends of the arm 15 are pins 17, said pins extending through the sides of the latch to engage in recesses 18 provided therefor in the standard 20 8. The ends of the pins 17 are beveled, as at 19, whereby the latch can be swung to a closed position and locked. The pins 17 are normally held within the recesses 18 by coil springs 20, encircling the contracted ends 21 65 of the pins 17, the opposite ends of said springs bearing against the sides of the concavity 14.

Countersunk in the outer side of the latch 12 for closing the concavity 14 is a plate 22, 70 secured to said latch by screws 23. This plate 22 is provided with a key hole 24 for the insertion of a suitable key (not shown), the key being adapted to engage in the key recess 25 provided therefor in the arm 15. 75

To cushion the closing movement of the latch 12, we employ a coil spring 26, which is mounted in the recess 10 of the standard 8.

When the latch 12 is locked in the closed position as illustrated in Figs. 2 and 3 of the 80 drawings, it is impossible for the switch arm 5 to be removed from the standard, without the use of a key. By inserting the key in the key hole 14, the arm 15 can be moved to withdraw the pins 17 from the recesses 18 of 85 the standard 8, and then the handles 13 of the latch can be elevated, to clear said latch from the slot 9 and permit of the arm 5 being elevated to move the switch tongue 6.

In Fig. 4 of the drawings, we have conventionally illustrated a semaphore switch 27 as having the support 28 thereof provided with our switch lock, the standard 8 thereof being bolted or otherwise secured to said support. 90

We reserve the right to use two locks in 95 connection with a switch for locking the switch arm in either position, but such an arrangement of the locks is very seldom necessary, as the switch is generally returned to its original position after being used.

It is thought that our invention will be 100 fully understood from the foregoing description taken in connection with the drawings, and we reserve the right to make such structural changes as are permissible by the appended claims.

Having now described our invention what we claim as new, is:—

1. The combination with a switch arm, of a slotted standard adapted to receive said arm, said standard being bifurcated and recessed, a latch pivotally mounted in the bi-

furecation of said standard and adapted to extend into said slot, a spring located in the recess of said standard for cushioning said latch, a pivoted arm located in said latch, 5 spring-pressed beveled pins pivotally connected to the ends of said arm and adapted to engage in said standard for holding said latch in a closed position, and means for engaging said arm and moving said pins from engagement with said standard, substantially as described.

2. The combination with a switch arm, of a slotted standard adapted to receive said arm, a pivoted latch mounted in said standard and adapted to hold said arm therein, 15 said latch having a concavity formed therein, spring-pressed beveled pins mounted in said concavity for engaging in said standard and holding said latch in a closed position, and an arm located within said concavity for moving 20 said pins out of engagement with said standard.

3. The combination with a switch arm, of a slotted standard adapted to receive said arm, a normally inclined latch pivoted in said standard and provided with a nose for maintaining the arm within the standard, 25 spring-pressed slidable pins mounted in said latch and adapted to be projected laterally therefrom for locking engagement with the standard to maintain the latch in inclined position, 30 said pins movable in opposite directions with respect to each other, means arranged within said latch for shifting said pins from position of locking engagement to release the latch so as to enable the withdrawal of the arm from the standard, and means engaging the said latch to cause it to assume an inclined position and to position the nose of the latch over the arm, said latch provided with a handle 35 permanently arranged clear of the standard.

tions with respect to each other and means arranged within said latch for shifting said pins from position of locking engagement to 35 release the latch so as to enable the withdrawal of the arm from the standard.

4. The combination with a switch arm, of a slotted standard adapted to receive said arm, a normally inclined latch pivoted in said standard and provided with a nose for maintaining the arm within the standard, spring-pressed slidable pins mounted in said latch and adapted to be projected laterally therefrom for locking engagement with the standard to maintain the latch in inclined position, 40 said pins movable in opposite directions with respect to each other, means arranged within said latch for shifting said pins from position of locking engagement to release the latch so as to enable the withdrawal of the arm from the standard, and means engaging the said latch to cause it to assume an inclined position and to position the nose of the latch over the arm, said latch provided with a handle 45 permanently arranged clear of the standard.

In testimony whereof we affix our signatures in the presence of two witnesses.

THOMAS LYCETT,
CHARLES DICKSON HOUSEMAN.
